UNITED STATES PATENT OFFICE.

KARL A. KENDRICK, OF DETROIT, MICHIGAN, ASSIGNOR OF ONE-FOURTH TO MINNIE C. BOOTH, OF DETROIT, MICHIGAN.

LAMP-OPERATING MECHANISM.

1,361,265.

Specification of Letters Patent. Patented Dec. 7, 1920.

Application filed December 17, 1917. Serial No. 207,408.

To all whom it may concern:

Be it known that I, KARL A. KENDRICK, a citizen of the United States, and residing at Detroit, in the county of Wayne and State of Michigan, have invented a new and Improved Lamp-Operating Mechanism, of which the following is a specification.

This invention relates to means for turning lamps of motor vehicles on horizontal and vertical axes so that the beams of light therefrom may be projected onto the roadway at any desired distance from the vehicle or may be projected toward either side of the line of movement of the vehicle as desired, and its object is to produce a simple and effective mechanism by means of which the lamps of a vehicle may be thus directed as desired through the agency of a single operating member which may be located most conveniently for the person driving the vehicle.

This invention consists, in combination with the lamps of a motor vehicle which are universally mounted to turn on horizontal and vertical axes, of actuating means for turning said lamps on either or both of said axes at will, and a single manually operated member for actuating said lamp-turning means.

20 In the accompanying drawings, Figure 1 is a side elevation of a lamp, its support and the mechanism for turning the lamp on a horizontal axis, and for turning the support of the lamp on its vertical axis. Fig. 2 is a plan of a pair of lamps and mechanism for turning them. Fig. 3 is a section of a connector. Fig. 4 is a plan of a lamp turned on its vertical axis out of its normal position. Fig. 5 is a front elevation of a lamp and a vertical section of its tubular support. Fig. 6 is a perspective of the operating mechanism of the lamp. Fig. 7 is a perspective of a segment secured to the lower end of the rod by means of 45 which the lamp is turned. Fig. 8 is a vertical section of the mechanism for operating the lamp. Fig. 9 is a plan of a lamp and of the rods connected thereto.

Similar reference characters refer to like parts throughout the several views.

Each lamp shown in the drawings is of any desired construction and is carried by means of a fork 2, but is revoluble on the support 3. This fork carries pivots 4 around which are wound the springs 5

which hold the lamp in ordinary horizontal position. A rod 6 extends down from the fork 2 through the support 3 and has secured to its lower end a circular member 7 of any desired length of arc, a segment 60 preferred, which segment is secured to this rod by means of a nut 8. This device may be mounted on a side bar 9 of the chassis of the vehicle, a pair of these devices being preferably mounted on each vehicle. A bracket 10 may be employed to connect the support 3 to the side bar 9 and a cap member 11 may be screwed on to the lower end of the tubular support 3. If desired, ball bearings may be mounted between the fork 65 2 and the tubular member 3, and between the cap 11 and the segment 7 in order to reduce the friction. A spring 12 on the stem 70 6 within the casing normally turns the lamp outward.

Mounted on the instrument board 13 of the vehicle is a circular plate 14 into which the tubular shaft 15 is secured. Connected to this plate 14 is a bar 16 which carries lugs 17. A pin 18 is mounted in these lugs and on it is pivoted a lever 19 by means of which this mechanism is manually operated. Slidable within the tubular shaft 15 is a rod 21, which is connected to the lever 19 by means of a short link 22. This rod is threaded or grooved at its outer end and may be engaged by means of the sharp inner end of a pin 24 which is connected to the bell crank lever 25, mounted on a small post 26 carried by the plate 14. If the rod 21 is to be moved in or out by means of the lever 19, the bell crank 25 will be turned to withdraw the pin 24 and the lever 19 may then be swung to move the rod 21 in or out. If desired, the plate 14 and the hollow shaft 75 90 95 15 and everything connected thereto may be turned as a unit.

Adjustably mounted on the hollow shaft 15 is a small spool 28 on which are wound the flexible connectors 29 and 30, preferably integral with each other, which connectors pass through the tubes 31 and attach to the segments 7 on the lower ends of the stems 6. By turning the shaft 21 and the spool 28 the connector 29 may be wound up and the connector 30 unwound to turn the lamps to the left, or the disk 14 may be turned in the opposite direction to turn the lamps to the right.

Flexible connectors are attached to the 110

lamps 1, as shown in Fig. 1, and then extend down and back through the tubes 33 to a block 34 in which they are positively held by means of screws 35. This block is 5 mounted on the member 36 which is connected to the stem 21 by means of a universal joint 37. When the stem 21 is drawn back by means of the lever 19, the connectors 32 will pull down the rear portions of the 10 lamps 1 against the tension of the springs 5 and cause the lamps to throw their beams of light upwardly. If the lever 19 is depressed the springs 5 cause the rays of light 15 to be projected downwardly. The flexible connectors specified above may be cords, chains, wires or tapes of any desired materials.

These operating devices for the lamps are 20 readily adjustable relative to the lever 19 by means of the set screw 38 which holds the drum 28 on the hollow shaft 15 and by means of the set screws 35 which secures the connectors 32 in position within the block 34. The initial positions of the lamps may 25 therefore readily be varied by releasing these set screws and swinging the lamps to the desired positions before again securing the screws.

The curvatures and lengths of the pipes 30 30 and 33 will depend upon the type of motor vehicle upon which this mechanism is installed. The details and proportions of the various parts may of course all be varied to meet the different problems presented by 35 the various types of motor vehicles on which these dirigible lamps are to be employed, by those skilled in the art without departing from the spirit of my invention as set forth in the annexed claims, and I do not, therefore, 40 wish to be limited except thereby.

I claim:—

1. A universal installation for vehicles comprising a pair of lamps and supports therefor, said lamps being pivotally mounted on horizontal axes, vertical rotatable supports for said lamps, springs mounted on the horizontal and vertical axes of the lamps to hold them in normal position, a slidable and rotatable rod, a drum rotatable with said rod and through which the rod is slidable, a pair of flexible connectors wound on said drum and connected to said vertical supports for the lamps whereby the lamps may be turned on their vertical axes, and another pair of flexible connectors attached to said rod and movable endwise thereby, said second pair of connectors being attached to the lamps to swing them on their horizontal axes against the force of the springs thereon. 45

2. A universal installation for vehicles 60 comprising a pair of lamps and supports therefor, said lamps being pivotally mounted on horizontal axes, vertical rotatable supports for said lamps, springs mounted on the horizontal and vertical axes of the lamps 65 to hold them in normal position, a slidable and rotatable rod, a drum rotatable with said rod and through which the rod is slid- 70 able, a pair of flexible connectors wound on said drum and movable endwise thereby, a second pair of flexible connectors attached to said rod and movable endwise thereby, one of said pairs of connectors being connected to said vertical supports for the lamps whereby the lamps may be turned on their 75 vertical axes, the other pair of connectors being attached to the lamps to swing them on their horizontal axes against the force of the springs thereon.

KARL A. KENDRICK.
